United States Patent Office

Des. 212,634

Patented Nov. 5, 1968

212,634

TOY VEHICLE

Frank Fusco, Monroe, Norman Charles Gold, New York,
and William Gold, Great Neck, N.Y., assignors to Louis
Marx & Co., Inc., New York, N.Y., a corporation of
New York

Filed Jan. 2, 1968, Ser. No. 10,032

Term of patent 14 years

(Cl. D34—15)

FIG. 1

FIG. 2

FIG. 3

FIG. 4

FIG. 1 is a top plan view of a toy vehicle embodying our new design;

FIG. 2 is a front elevational view thereof;

FIG. 3 is a left side elevational view thereof, the right side constituting a mirror image thereof; and

FIG. 4 is a rear elevational view thereof.

We claim:

The ornamental design for a toy vehicle, as shown and described.
